AMPLIFICATION CONTROL SYSTEM

David Grimes, Dongan Hills, Staten Island, N. Y.,
assignor to Radio Corporation of America, a
corporation of Delaware

Application April 26, 1932, Serial No. 607,535

15 Claims. (Cl. 250—20)

My present invention relates to amplification control, and more particularly to a novel method of, and means for, controlling the gain of a radio receiver in such a manner that it is maintained substantially uniform over a predetermined frequency range.

It is well known, especially in superheterodyne reception, that a tunable radio frequency circuit inherently tends to increase in transmission efficiency as the frequency of the range being amplified increases. Stated in other words, it is a well known fact that the gain of a radio frequency amplifier using constant grid bias varies directly with frequency of the amplified energy. In superheterodyne receivers, however, there exists an effect which can be taken advantage of to overcome the aforementioned inherent characteristic of tunable radio circuits. It is understood, of course, that in a radio receiver it is extremely desirable to maintain the maximum gain substantially uniform over the operating frequency range of the receiver.

The oscillator plate current increases with frequency in the local oscillator circuit of a superheterodyne receiver, and, hence, there is provided a device which can be readily employed for overcoming the inherent tendencies of the radio frequency circuits to increase their transmission efficiency with frequency. Now, I have discovered a method of, and means for, taking advantage of the aforementioned phenomenon, and it may be briefly stated that the present invention involves utilizing oscillator plate current to vary the bias of the amplifier grids in that direction which will tend to overcome the inherent tendency of the radio frequency circuits to increase in transmission efficiency with frequency.

Accordingly, it may be stated that it is one of the main objects of my present invention to provide in a radio receiver employing radio frequency circuits normally tending to increase in transmission efficiency with frequency, a circuit adapted to supply a biasing potential to the amplifier which varies with frequency variation in such a manner that the aforementioned tendency is constantly balanced.

Another important object of the present invention is to provide a superheterodyne receiver with a radio frequency amplification circuit having substantially uniform gain over the operating frequency range, such substantial uniform gain being produced by employing the local oscillator plate current, which increases with frequency, to effect biasing of the radio frequency amplifier.

Another object of the present invention is to provide a superheterodyne receiver arranged to maintain a constant intermediate frequency difference throughout a predetermined frequency range, and, additionally, to arrange the local oscillator circuit in such a manner with respect to the radio frequency amplifier and the frequency changer circuits that substantially uniform radio frequency amplification is secured over the said frequency range.

And still other objects of the present invention are to improve generally the simplicity and amplification efficiency of radio receivers, and to particularly provide a superheterodyne radio receiver which is not only reliable in operation, but substantially uniform in its radio frequency transmission and economically manufactured and assembled.

The novel features which I believe to be characteristic of my invention are set forth in particularity in the appended claims, the invention itself, however, as to both its organization and method of operation will best be understood by reference to the following description taken in connection with the drawings in which I have indicated diagrammatically several circuit organizations whereby my invention may be carried into effect.

In the drawings,

Fig. 1 diagrammatically shows a receiver embodying the present invention,

Fig. 2 diagrammatically shows a receiver embodying a modified form of the invention.

Referring now to the accompanying drawings in which like characters of reference indicate the same parts in the different figures, there is shown, in Fig. 1, a superheterodyne receiver consisting of the usual grounded antenna circuit A, G, which is coupled, as at M, to the tunable input circuit of a screen grid tube 1. The said input circuit includes a variable tuning condenser 2 which has its rotor grounded, as at 3, a radio frequency bypass condenser 4 being connected between the grounded side of the rotor and the low potential terminal of the secondary of the coupling means M.

The anode of the tube 1 is arranged to have suitable positive potential supplied to it through the primary of a coupling transformer M₁. The screen grid of the tube 1 is arranged for application thereto of a suitable positive potential from a source (not shown) S. The cathode heating source, the screen grid source, and the anode potential source are not shown, but it is to be clearly understood that these may comprise battery,

or commercial power line, sources, and since such devices are well known to those skilled in the art, they need not be referred to in any further detail.

5 The output circuit of the radio frequency amplifier is coupled, as at M_1 , to the tunable input circuit of a screen grid tube 5. A variable tuning condenser 2', having its rotor grounded, as at 3', is arranged in the input circuit of tube 5. 10 The radio frequency by-pass condenser 4' is connected in the same manner as shown in the input circuit of tube 1. Tube 5 is included in the frequency changer, or first detector, stage. A radio frequency by-pass condenser 6 is shunted 15 across the primary of the coupling device M_2 , the latter coupling the output of the first detector to the input of the intermediate frequency amplifier 7.

The amplifier 7 is shown in conventional form, 20 and since the construction of the amplifier is very well known to those skilled in the art, it need not be described in any further detail. The amplified intermediate frequency energy is, of course, detected in a second detector; the output 25 of the second detector is, then, amplified in an audio frequency amplifier, and subsequently utilized in any desired manner, as by headphones, loud speaker, or any other type of reproducer. Since the present invention applies particularly 30 to the radio frequency amplifier, first detector and local oscillator circuits, it is not believed necessary to describe the portion of the receiver following the first detector any further.

The local oscillator circuit comprises a screen 35 grid tube 8 having an inductance coil 9 connected between its control electrode, or grid, and its cathode. In series with the cathode and the coil 9 there is arranged a resistor 10 which is used for a purpose to be shortly described. The 40 variable tuning condenser 11 is connected in shunt with the coil 9, the rotor of the condenser being grounded, as at 12. The anode of the tube 8 is inductively coupled, as at M_3 , to its input circuit, the potential source 13 having its positive 45 terminal connected to the anode, and its negative terminal connected to the low potential side of the resistor 10. By means of the leads 19 and 19' the low potential terminals of the inductances included respectively in the tuned input 50 circuits of the amplifier and detector are connected to the low potential side of the resistor 10.

A radio frequency by-pass condenser 14 has one of its terminals connected to the positive side of the source 13, and its other terminal grounded. 55 The screen grid of the tube 8 is shown connected by an adjustable lead 15 to the source 13 so that appropriate positive potential may be applied to the screen grid.

The rotors of the condensers 2, 2' and 11 are 60 shown connected by dotted lines, to a common, or uni-control, tuning device 16. It is to be understood that the mechanical coupling of the rotors of these various tuning condensers may be arranged in any desired manner well known 65 to those skilled in the art. For example, the three condensers may be arranged in a common housing, in the well known "bath-tub" construction manner, and in such case the three condensers will be similar. In order to tune the 70 local oscillator through a frequency range differing from the frequency range of the radio frequency amplifier and first detector by a constant amount, which amount equals the desired intermediate frequency, resort may be had to the well known series-shunt fixed condenser con-

struction disclosed by W. L. Carlson in his U. S. Patent 1,740,331 of December 17, 1929.

Briefly, this arrangement comprises a fixed condenser 17 connected in series between the condenser 11 and the inductance coil 9, and a 5 fixed condenser 18 connected in shunt with the tuning condenser 11. As explained in the Carlson patent, appropriate design of these condensers results in securing a constant intermediate frequency difference throughout the operating range of the uni-control device 16. Of course, more than one radio frequency amplification stage may be employed preceding the first detector, but in order to preserve simplicity of description only a single stage is shown. 15

The operation of the receiver shown in Fig. 1 will now be described with particular attention directed towards the functioning of the present invention. Those skilled in the art well know that signal energy collected by the antenna circuit A, G is impressed upon the input of the radio frequency amplifier, the amplified energy then being impressed upon the input of the first detector which is tuned to the signal frequency. The local oscillator circuit is coupled, as at M_4 , 20 to the input of the first detector, and, hence, impresses upon the input of the first detector, energy of a frequency differing from the signal frequency by the desired intermediate frequency. 25

The input of the intermediate frequency amplifier is maintained fixedly tuned to the desired intermediate frequency, and there will be transmitted intermediate frequency energy from the first detector output to the input of the intermediate frequency amplifier. As stated, heretofore, the oscillator plate current increases with 30 frequency, and therefore the drop of potential across the resistor 10 will vary directly with frequency. This latter relation follows in virtue of the fact that the resistor 10 is disposed in the 35 plate to cathode current path of tube 8. It is not believed necessary to go into the theoretical, or physical, explanation of how the plate current increases with frequency, since it is believed necessary to merely point out that those skilled in 40 the art are well aware of such a phenomenon. 45

By connecting the grids of tubes 1 and 5 to the low potential side of resistor 10, it is possible to regulate the bias of these grids in such a manner that the gain in the radio frequency amplifier stage and the frequency changer stage will be substantially uniform over the operating range of the receiver. This is accomplished in virtue 50 of the fact that, as the three tuned circuits are varied in resonance to increasing frequencies the 55 bias on the grid of each of tubes 1 and 5 becomes increasingly more negative since the drop across the resistor 10 becomes increasingly greater. Thus, the inherent tendency of tubes 1 and 5 and associated circuits to increase their gain with 60 increasing frequencies is overcome, for the increasing negative bias functions to reduce the gain.

It should, also, be noted that the increasing bias on the frequency changer tube insures sufficient bias at the frequencies where the strongest heterodyne voltage is impressed upon the frequency changer tube. Thus, it will be seen that the local oscillator resistor 10 is connected to the radio frequency amplifier circuit for regulating 70 the latter in such a manner that the amplification of the radio frequencies does not increase at the higher frequencies to the extent that it would with constant bias, and cooperates with the frequency changer circuit to insure sufficient bias 75

at the frequencies where the strongest heterodyne voltage is impressed upon the frequency changer tube.

It will now be appreciated that there is disclosed in the present application a general method for utilizing a biasing potential which is a function of frequency, especially a bias potential derived from an oscillator circuit. This general method is shown specifically utilized in a superheterodyne receiver which necessarily includes an oscillator circuit, the bias potential derived from the superheterodyne oscillator being employed for remedying undesirable effects inherent in the operation of the radio frequency amplifier and 10 the first detector.

Hence, it should be recognized that the present invention is not limited to the specific receiver shown in Fig. 1 inasmuch as other uses for the basic principle disclosed herein will be readily 20 thought of by those skilled in the art. For example, the receiver need not necessarily be of the superheterodyne type, but may incorporate a local oscillator for the sole purpose of producing a variable bias potential which is a function of 25 frequency for the purpose of controlling the gain of the radio frequency amplifier. Again, an independent local oscillator need not necessarily be employed, since the present invention is equally applicable to the construction wherein a combined 30 detector oscillator circuit is employed between the intermediate frequency amplifier and the radio frequency amplifier.

Of course, it is apparent that the tunable radio frequency circuits may be utilized between the 35 antenna and the frequency changer tube without employing any radio frequency amplification. In such cases, the oscillator bias would be applied to the frequency changer, the intermediate frequency amplifier, or even the audio amplifier to 40 effect substantially uniform over-all gain.

A modified form of the invention is disclosed in Fig. 2, wherein advantage is taken of the fact that as the oscillator plate current increases with frequency, the positive potential of the oscillator 45 cathode increases with frequency. In describing Fig. 2 only those portions of the arrangement which differ from that shown in Fig. 1 will be discussed. In view of the fact that similar elements of both figures are correspondingly numbered it 50 is not believed necessary to describe the construction in great detail. The cathode of oscillator 8 is connected to ground through the biasing resistor R₃. Suitable variable taps 23 and 25 on said resistor are connected respectively to the 55 cathodes of radio frequency tube 1 and frequency changer tube 5 through lead 22 and self-biasing resistor R₁ and lead 24 and self-biasing resistor R₂. The grids of tubes 1 and 5 being grounded, the potential of each with respect to its associated 60 cathode will depend on the voltage drop through the resistors between cathode and ground. For example, the grid bias of radio frequency tube 1 will be the sum of the voltage drop across self-biasing resistor R₁ and that across the portion 65 of R₃ between tap 23 and ground. The grid bias of frequency changer 5 will be the sum of the voltage drop across self-biasing resistor R₂ and that across the portion of R₃ between tap 25 and ground.

70 Appropriate radio frequency by-pass condensers 20, 21 are connected between the cathodes and grids of tubes 1 and 5, while a tap on the oscillator circuit for the grid connection is desirable to reduce the effect of the tube capacity 75 on tuning. This is likely to cause parasitic oscil-

lations of high frequency. These may be avoided by adding a condenser C of sufficient magnitude. The more tightly coupled the two portions of the grid coil, the less the value of C required to avoid parasitic oscillations. The effect of the condenser C is to make the tendency of the oscillator to 5 oscillate more strongly at high frequencies than at low frequencies even more pronounced. This may be desirable, in which case C may be made even larger than the value required to stop parasitics. 10

The operation of the modification shown in Fig. 2 is similar to that described in connection with the arrangement shown in Fig. 1. As in the latter arrangement it is pointed out that since 15 the translation gain of the radio frequency amplifier stage is a function of the product of the signal energy and the oscillation energy, as the amplification of the signal energy inherently tends to increase with increasing frequencies, it 20 is merely necessary to utilize the increase of plate current of the oscillator to decrease the amplification of the signal energy.

While I have indicated and described several 25 systems for carrying my invention into effect, it will be apparent to one skilled in the art that my invention is by no means limited to the particular organizations shown and described, but that many modifications may be made without departing 30 from the scope of my invention as set forth in the appended claims.

What I claim is:

1. In a superheterodyne receiver, a radio frequency amplifier including an electron discharge tube, a frequency changer including an electron discharge tube, a local oscillator including an electron discharge tube, a common means for tuning said amplifier and frequency changer to a desired signal frequency, additional means, simultaneously operative with said common 35 means, for tuning said local oscillator to a frequency differing from said desired signal frequency by a predetermined intermediate frequency, and connections between said local oscillator and said amplifier whereby the direct-current bias for the grid of said amplifier tube increases with increasing signal frequency so that the amplification of the radio frequency tube does not increase at the higher frequencies to the extent that it would with constant grid bias, said connections comprising a resistor and a shunt capacity disposed between the grid and cathode of the oscillator tube and a conductor connected 40 between a point on said resistor and one of the electrodes of said amplifier tube. 45

2. In a wave repeating system, a plurality of stages connected in cascade, a vacuum tube in each of said stages, a local oscillator, a resistor and a shunt capacity connected in a circuit of said local oscillator, so that the direct-current potential drop through the resistor changes with changes in the frequency of oscillation of the oscillator, means for tuning the input of one of said cascade connected stages, means for varying the resonant frequency of said local oscillator, uni-control means for both of the last mentioned means, and a direct current connection from said resistor to a grid electrode in the tube in one of said cascade connected stages for biasing said grid electrode in accordance with the resonant frequency of said local oscillator. 50

3. In a wave repeating system, a plurality of stages connected in cascade, a vacuum tube in each of said stages, a local oscillator, a resistor 55

- and a shunt capacity connected in a circuit of said local oscillator, so that the direct-current potential drop through the resistor changes with changes in the frequency of oscillation of the 5 oscillator, a variable condenser for adjusting the resonant frequency of said local oscillator, variable condensers for adjusting the resonant frequency in a plurality of said cascade connected stages, uni-control means for said variable condensers; and connections from said resistor to the input circuits of a plurality of said cascade connected stages for applying the potential drop across said resistor to the grid electrodes of the tubes in said stages as a biasing potential.
- 15 4. A superheterodyne radio receiver comprising a plurality of cascade connected stages, one of said stages constituting a first detector, tuned input circuits in a plurality of said cascade connected stages, at least one of said tuned input 20 circuits being variable, a vacuum tube in each of said stages, a local oscillator, a tuned circuit for adjusting the resonant frequency of said local oscillator, means coupling said local oscillator to said first detector, a resistor and a shunt capacity 25 connected in the circuit of said local oscillator so that the direct-current potential drop across said resistance varies with the resonant frequency of said oscillator, and connections for biasing the grid of the tube in one of said stages 30 from the potential drop across said resistor.
5. A superheterodyne radio receiver comprising a plurality of cascade connected stages, one of said stages constituting a first detector, tuned input 35 circuits in a plurality of said cascade connected stages, at least one of said tuned input circuits being variable, a vacuum tube in each of said stages, a local oscillator, a tuned circuit for adjusting the resonant frequency of said local oscillator, means coupling said local oscillator to 40 said first detector, a resistor and a shunt capacity connected in the circuit of said local oscillator so that the direct-current potential drop across said resistance varies with the resonant frequency of said oscillator, and connections from 45 said resistor to the cathode and grid electrodes of the tubes in a plurality of said stages for applying biasing potentials to the grids of those stages.
6. A superheterodyne radio receiver comprising a plurality of cascade connected stages, one of said stages constituting a first detector, tuned input 50 circuits in a plurality of said cascade connected stages, at least one of said tuned input circuits being variable, a vacuum tube in each of said stages, a local oscillator, a tuned circuit for adjusting the resonant frequency of said local oscillator, means coupling said local oscillator to 55 said first detector, a resistor and a shunt capacity connected in the circuit of said local oscillator so that the direct-current potential drop across said resistance varies with the resonant frequency of said oscillator, and connections from 60 said resistor to the input circuit of said first detector for biasing the grid of said first detector from the potential drop across the resistor.
- 65 7. A superheterodyne radio receiver comprising a plurality of cascade connected stages, one of said stages constituting a first detector, tuned input circuits in a plurality of said cascade connected stages, at least one of said tuned input circuits being variable, a vacuum tube in each of said stages, a local oscillator, a tuned circuit for 70 adjusting the resonant frequency of said local oscillator, means coupling said local oscillator to said first detector, a resistor and a shunt capacity

connected in the circuit of said local oscillator so that the direct-current potential drop across said resistance varies with the resonant frequency of said oscillator, uni-control means connecting the tuning means of said local oscillator and the tuning means in said stage having a variable tuned input circuit, and connections for biasing the grid of the tube in the last mentioned stage according to the potential drop across said resistor.

10 8. A superheterodyne radio receiver comprising a plurality of cascade connected stages, one of said stages constituting a first detector, tuned input 15 circuits in a plurality of said cascade connected stages, at least one of said tuned input circuits being variable, a vacuum tube in each of said stages, a local oscillator, a tuned circuit for adjusting the resonant frequency of said local oscillator, means coupling said local oscillator to said first detector, a resistor and a shunt capacity 20 connected in the circuit of said local oscillator so that the direct-current potential drop across said resistance varies with the resonant frequency of said oscillator, and connections from said resistor to the input circuit of the stage preceding said first detector for biasing the grid of the tube in that stage.

9. A superheterodyne radio receiver according to claim 4, in which said resistor is connected in the circuit of said local oscillator so as to be 30 common to the input and output circuits thereof.

10. In a superheterodyne radio receiving system including a plurality of cascade connected radio frequency stages and a local oscillator coupled to one of said stages for producing an intermediate 35 frequency, said local oscillator having a resistor and a shunt capacity connected in its plate to cathode circuit, the method of biasing the grids of the tubes in a plurality of said radio frequency stages of said receiver which consists of utilizing 40 the direct-current potential drop across said resistor as a source of biasing potential.

11. In a superheterodyne receiver provided with several stages and a local oscillator, the method of controlling uniformly the over-all amplification 45 of the receiver over its entire frequency range, which comprises deriving from the local oscillator a direct current voltage proportional to the oscillator frequency, and applying said direct current voltage to one or more of the stages in a sense 50 to compensate for the inherent tendency thereof to increase the amplification with increase in frequency.

12. In a superheterodyne receiver provided at least with a detector and a local oscillator which are coupled together to produce a difference frequency, the method of controlling uniformly the over-all amplification of the receiver over its entire frequency range, which comprises deriving from the local oscillator a direct current voltage 60 which is proportional to the oscillator frequency, and applying said voltage to the detector in a sense to compensate for the inherent tendency thereof to increase the amplification with increase in frequency.

13. A radio frequency circuit of the superheterodyne type having at least a radio frequency amplifier, a detector and a local oscillation generator, means for coupling said local oscillation generator to said detector for producing a difference frequency, and means independent of said coupling means for deriving a direct-current potential from said oscillation generator and applying said potential to the control electrodes of both the 70 amplifier and detector, said last-mentioned means 75

comprising a resistance and a shunt capacity included in the circuit of the oscillation generator and direct-current connections from said resistance to the control electrodes of said amplifier and detector.

- 5 14. A radio receiving circuit of the superheterodyne type having at least a radio frequency amplifier, a detector and a local oscillation generator, means for coupling said local oscillation generator 10 to said detector for producing a difference frequency, and means independent of said coupling means for deriving a direct-current potential from said oscillation generator and applying said potential to the control electrode of the amplifier, 15 said last-mentioned means comprising a resistance and a shunt capacity included in the circuit of the oscillation generator and a direct-current

connection from said resistance to the control electrode of said amplifier.

15. A radio receiving circuit of the superheterodyne type having at least a detector and a local oscillation generator, means for coupling said 5 oscillation generator to the detector for producing a difference frequency, and means independent of said coupling means for deriving a direct-current potential from said oscillation generator and applying said potential to the control electrode of the detector, said last-mentioned means comprising a resistance and a shunt capacity included in the circuit of the oscillation generator and the direct-current connection from said resistance to the control electrode of said detector. 10 15

DAVID GRIMES.
